United States Patent

Des. 241,601
Patented Sept. 28, 1976

241,601

COMBINED SKILLET AND CHAFING DISH OR THE LIKE

William Joseph Cook, Trumbull, Conn., assignor to
General Electric Company

Filed Sept. 6, 1974, Ser. No. 503,643

Term of patent 3½ years

Int. Cl. D7—02

U.S. Cl. D7—90

FIG. 1.

FIG. 2.

FIG. 4.

FIG. 1 is a front perspective view of a combined skillet and chafing dish or the like showing my new design;

FIG. 2 is a sectional view taken on line 2—2 of FIG. 1;

FIG. 3 is an exploded perspective view of the combined skillet and chafing dish shown in FIG. 2; and

FIG. 4 is a view of the bottom of the combined skillet and chafing dish.

The rear view is identical to that shown in FIG. 1.

I claim:

The ornamental design for a combined skillet and chafing dish or the like, substantially as shown.
